UNITED STATES PATENT OFFICE.

RICHARD SMITH, OF SHERBROOKE, QUEBEC, CANADA, ASSIGNOR OF ONE-FIFTH TO
CHARLES WALTER CATE, OF SHERBROOKE, QUEBEC, CANADA.

ROTARY ENGINE.

1,158,325.

Specification of Letters Patent.

Patented Oct. 26, 1915.

Application filed January 4, 1915. Serial No. 419.

To all whom it may concern:

Be it known that I, RICHARD SMITH, a citizen of the Dominion of Canada, and resident of the city of Sherbrooke, in the 5 Province of Quebec and Dominion of Canada, have invented certain new and useful Improvements in Rotary Engines, of which the following is a full, clear, and exact description.

10 This invention relates to improvements in rotary engines, and is designed as an improvement on the apparatus disclosed in my former Patents, Nos. 646,392 and 646,393.

15 The object of the invention is to provide an engine of the rotary piston type adapted to utilize the full expansive force of steam or other fluid under pressure.

20 A further object is to provide an engine of extreme simplicity and durability, which may be manufactured at small expense.

25 Various other objects and advantages will be apparent from the following description.

The device consists essentially of a cylindrical casing containing a rotor having a substantially radially projecting portion. The inlet to and exhaust from said casing are placed approximately 285 degrees or more apart, so that the expansion is practically double that of a reciprocating engine. Furthermore, the leverage of the 30 large diameter rotor utilizes the power of the motive fluid to the greatest advantage. Gates are provided between the inlet and exhaust passages which act as a cylinder head.

35 In the drawings which illustrate the invention:—Figure 1 is a side elevation of the engine showing one half of the side plate removed. Fig. 2 shows on the left a half end elevation and on the right a half central section. Fig. 3 is a section on the line 3—3, Fig. 1. Fig. 4 is a section on the line 4—4, Fig. 1. Fig. 5 is a side view of one of the inlet cams. Fig. 6 is a fragmentary view of the rotor bearing surface of the casing. Fig. 7 is a view similar to Fig. 3, showing an alternative form of gate.

40 Referring more particularly to the drawings, 11 designates a base upon which is mounted a circular body casing 12 having side plates 13. The body and its side plates forming the casing are provided with a continuous jacket 14, so that the machine may be kept warm or cool according to the motive fluid used.

45 The body 12 is divided by a central partition 15 so as to form with the covers two chambers or cylinders 16 and 17. Between the periphery and the central shaft 18, the body and covers are each provided with broad flanges 19, which approach closely to one another and substantially restrict the cylinders 16 and 17 to annular form, as clearly shown in Figs. 1 and 2.

50 The shaft 18 which is mounted in roller 65 bearings 20 in the covers carries a pair of rotors, each consisting of a circular blade 21 having an approximately radially projecting arm 22, an arbor 23, and a piston 24 mounted on the arm 22. The arm 22 previously mentioned as approximately radial 70 is turned very slightly out of the true radial direction, and its axis is substantially tangential to a small circle of about the same diameter as the shaft. The object of this is 75 to have the angular direction of the arm when the rotor is revolving in the direction of the arrow compensate for the centrifugal force acting on the piston, so that the piston does not press any harder on the outside of 80 the casing than it does against the flanges 19. The faces of the flanges 19, against which the blades 21 of the rotor bear, are provided with suitable packing, so that fluid tight joints are maintained. This packing, 85 designated 25, may be of any suitable shape such as shown in Fig. 6.

90 The gate 27, which is provided between the inlet and exhaust, is mounted in a suitable housing 28 and is radially disposed, as clearly seen from Fig. 1. The gate is carried and operated by a spindle 29 toothed at its free end to form a rack 30. A rocker 31 toothed at both ends is mounted on a rack 32 carried by an extension 33 of the 95 housing 28, and is operated by a slide 34 pivotally connected to it intermediate its ends. The slide 34 carries a small roller 35 which engages the irregular curve of a cam 36 on the shaft 18. Both the slide 34 100 and the gate spindle 29 are mounted in suitable guides 37 carried on the plate 33. The gate when in retracted position is entirely clear of the annular cylinders, but when in its normal advanced position, completely blocks the cylinders resting in a well fitting groove 38.

105 The inlet valve shown in detail in Fig. 4, consists of a body 39 mounted on the cover and containing a valve 40 normally main- 110

tained closed by a spring 41. A valve stem 42 projects through the casing and is provided at its free extremity with a roller 43 engaging a cam 44 mounted on the shaft. 5 The supply pipe 45 is connected to the valve case 39 on the opposite side of the valve from the inlet port 46. The cam 44 is preferably made of two disks 47, each having a comparatively short projecting portion or throw 48, and each provided with circularly curved slots 49, through which set screws 50 may be passed to clamp the disks in any desired relation to a hub 51 fixed to the shaft. 10

15 In Fig. 7 a slightly alternative form of gate is shown. Instead of being in a single piece as in Fig. 3, this gate is divided in the center and the parts move in opposite directions. The gate parts 52 are each rabbed at 53 so as to overlap and make a fluid tight joint when closed. One gate has an angularly projecting arm 54 at the top, and the other has a similar arm at the bottom operating through a gate case 55. In 20 each arm 54, one end of an oscillating lever 56 is engaged by means of a ball and socket joint. The rocking lever is operated by a lever 57 outside the gate case, which is connected by a link 58 with any suitable member 59 carrying a roller 60 engaging a suitable cam 61 rigidly mounted on the shaft. 25

It will be understood that in the drawings a double unit is shown, that is, one having two rotors in a single casing. The 30 inlet and exhaust and the gates of these two rotors are of course on opposite covers, and are in addition diametrically opposite one another, so that while each rotor only receives one charge of motive fluid per revolution of the shaft, the entire machine receives two such charges per revolution. It 35 is obvious that a machine may be built with a single rotor, but a double unit is much more economical to build and much more 40 powerful. It will also be obvious that a number of such double units may be connected on a single shaft. When steam is used as a motive fluid, the jacket of the casing may be connected to the supply pipe 45 45 by a suitable pipe 62.

The operation of the apparatus is extremely simple and is almost obvious from the foregoing description. In brief, the operation is as follows:—The inlet valve 40 50 is opened by the revolution of its cam 44 as soon as the piston passes the inlet port, and remains open a suitable length of time, admitting motive fluid under pressure between the piston and gate, which is normally 55 closed. This motive fluid drives the piston in the direction of the arrow until the supply is cut off, and after cut off, the expansion of the fluid continues to drive the piston, thus rotating the shaft. When the 60 piston uncovers the exhaust port, the fluid 65

escapes. When the piston approaches very closely to the gate, the irregularity of the cam 36 operates the slide 34, which shifts the rocking lever 31 and withdraws the gate for the passage of the piston. The gate is 70 closed after the piston in the same manner and remains closed. As soon as the piston passes the inlet port, a fresh charge is admitted. The exhaust remains always open so that the piston at each revolution drives 75 out what remains of the previous charge. The time and duration of opening of the inlet may be regulated by shifting the disks 47 of the cam 44 relatively to one another and to the hub 51, so as to alter the position 80 and length of the throw 48.

The operation of the modified form of gate shown in Fig. 7 is extremely simple. The oscillating lever when shifted operates the gates always in opposite directions, that is, toward one another or away from one another. Each form of gate has its own peculiar advantages. The form shown in Fig. 3 is all external and may be easily tended. The form shown in Fig. 7 is largely 90 inclosed, but has the advantage of slightly quicker operation.

Having thus described my invention, what I claim is:—

1. In a device of the character described, 95 a casing, forming an annular chamber, a rotor in said casing having a non-radial arm, and a piston mounted on the arm, said arm being disposed tangentially to a circle smaller than the rotary to counteract centrifugal force acting on the piston.

2. In a device of the character described, 100 a casing having a pair of annular chambers therein, gates traversing said chambers arranged on opposite sides of the casing and 105 on opposite sides of the casing axis, a shaft passing through the casing, rotors thereon, pistons carried by the rotors, cams on the shaft, and cam operated rocker mechanism arranged to open and close said gates for 110 the passage of the pistons.

3. In a device of the character described, 115 a casing having a central chamber and a surrounding annular chamber, a reduced annular passage connecting the central and surrounding chambers, a rotor including a thin blade occupying the passage and a piston loosely mounted on the blade occupying the annular chamber, and packing of reverse curve form in the walls of said passage engaging the rotor.

4. In a device of the character described, 120 a casing, a shaft passing axially therethrough, a pair of annular chambers in said casing, a central wall separating said chambers, an inlet and exhaust passage for each chamber arranged in close proximity, a gate traversing each chamber between said exhaust and inlet, the passages and gate of one chamber being on opposite sides of the 125 130

casing and opposite sides of the axis from those of the other chamber, a rotor in the casing having a pair of pistons each occupying a chamber, means operating said gates, 5 an inlet valve on each inlet passage, and adjustable means operating said valves subsequent to the operation of the adjacent gate.

5. A device of the character described, comprising the combination with a casing, 10 having an annular chamber therein, of a shaft, a rotor on said shaft, a piston on the rotor occupying said chamber, a gate traversing the chamber, a lever pivotally mounted intermediate its ends, a sliding connection between said lever and the gate, and cam operated means connected to the lever at its pivotal point arranged to open and close the gate for the passage of said piston.

6. A device of the character described, 20 comprising the combination with a casing having an annular chamber therein, of a shaft, a rotor on said shaft, a piston on the rotor occupying said chamber, a gate traversing the chamber, a rack toothed spindle

for said gate, a fixed rack, a rocking lever 25 toothed at its ends engaging between said racks, a slide pivotally connected to the lever intermediate its ends, and a cam on the shaft arranged to operate said slide at predetermined intervals.

7. In a device of the character described, the combination with a casing, an axially disposed shaft, and a rotor on said shaft, of an inlet passage for the casing, an outlet 30 passage, a valve controlling the inlet passage, an operating cam for said valve mounted on the shaft, said cam comprising a hub fixed to the shaft, a pair of similar slotted cam disks revolvably mounted on the shaft, and means releasably holding said disks in predetermined relation with one another and with the fixed hub.

In witness whereof, I have hereunto set my hand, in the presence of two witnesses.

RICHARD SMITH.
